UNITED STATES PATENT OFFICE.

WILLIAM B. WADDELL, F BETHLEHEM, MARYLAND.

POST.

1,097,110.

Specification of Letters Patent. Patented May 19, 1914.

Application filed September 13, 1913. Serial No. 789,702.

To all whom it may concern:-

Be it known that I, WILLIAM B. WADDELL, a citizen of the United States, residing at Bethlehem, in the county of Caroline and State of Maryland, have invented certain new and useful Improvements in Posts, of which the following is a specification, reference being had to the accompanying drawings.

10 This invention relates to new and useful improvements in posts and more particularly to the supporting base and the manner of mounting the posts thereon, the object of the invention being to provide a base which is preferably constructed of metal and buried within the ground so that the upper end thereof projects just above the surface, the posts being removably mounted upon the upper end of the base and to be constructed of wood or any other desirable material so that should the same become decayed or worn, it may be quickly and readily removed and replaced by a new one.

Another object of the invention is the provision of novel means for mounting the post upon the base and also to provide novel means for removably securing the post to the upper end of the base.

A further object of the invention is the provision of a post of this character which will possess advantages in points of efficiency and durability, is inexpensive of manufacture and at the same time is simple in construction and operation.

35 With the above and other objects in view, this invention consists in the novel features of construction and the combination and arrangement of parts to be hereinafter more fully described, pointed out in the claim and shown in the accompanying drawings, in which—

Figure 1 is a side elevation of a fence post constructed in accordance with my invention; Fig. 2 is a front elevation; Fig. 3 is a 45 transverse sectional view of the post taken on the line 3—3 of Fig. 2; Fig. 4 is a transverse sectional view of the base member taken on the line 4—4 of Fig. 1; Fig. 5 is a detail perspective view of one of the securing members; and Fig. 6 is a bottom plan view illustrating a slightly modified form of base.

Referring more particularly to the drawings, 1 indicates my improved base portion which is preferably formed with a central body member 2 from which projects the ra-

dial blade portions 3. These blade portions 3 are preferably arranged in opposed relation, as illustrated in Fig. 4, so as to provide a sufficient space between the same in which the dirt is arranged so as to prevent any rotary movement of the base after being inserted within the ground. The body portion 2 of the base may be constructed in any desirable manner, that is, it may be formed 65 circular in cross section and provided between the blade portions 3 with flat portions 4 which form a suitable space between the inner ends of the blade members 3, but it will be understood that the body portion 2 70 will be constructed in any desirable manner.

Secured to one end of the base and adapted to rest upon the ends of the blades 3 and the body 2 is a plate 5, to the upper face of which are secured the guide rails 6, said 75 guide rails being arranged in spaced parallel relation and provided with inwardly inclined walls 7. These guide rails 6 may be of any desired form in cross section and are to be secured to the plate 5 by means of 80 screws, nails or any other similar fastening means of this character, as shown at 8. The post 9 which, while herein shown and described as preferably rectangular in cross section, may, if desired, be circular in cross 85 section and provided at its base with a rectangular portion adapted to fit between the rails 6 so that my improved base, while herein shown and described as applied to a fence post, may be used equally as well in supporting telephone, telegraph and any other 90 similar pole or post of this character.

The post 9, as shown in the accompanying drawings, is provided at its lower end and upon opposite sides thereof with the 95 reduced portion 10 having inclined side walls 11 which are formed coincident with the inclined side walls 7 of the rails 6 so that the reduced portion 10 will readily fit between the rails, the shoulder 12 formed by 100 the inclined portions 11 being adapted to rest upon the upper edges of the rails 6.

The post is securely held, when in its operative position, against longitudinal movement by means of the fastening members 13, 105 said fastening members being formed of metal and including an elongated body, one end of which is flattened, as shown at 14, and disposed at right angles to the body and the other end thereof being circular in form 110 and arranged in alinement with the end 14. The lower end of the post is provided at

opposite sides thereof with vertical grooves 15 which communicate at one end with the recesses 16 and at the other end with the notches 17 formed in opposite sides of the 5 plate 5 and adapted to receive the body portion of the fastening members. The body portion of the fastening members, as shown in the accompanying drawings, is disposed within the groove in the body and the notch 10 17, one end of the fastening members being engaged beneath the plate 5, while the other end thereof is arranged within the opening 16 so as to prevent movement of the posts when arranged in position.

15 It will be readily noted from the construction of my improved fence post, that the same eliminates the necessity of digging post holes, the base portion thereof can, if necessary, be driven into the earth, this being the 20 preferred way of placing the same in position and it will be noted that the post member 9 can be quickly and readily applied to the top of the base or removed therefrom. It will also be apparent from the peculiar 25 arrangement of the blades 3 that any strain will be equally divided, that is any radial movement of the post or base portion will be absolutely prevented by the rotary arrangement of these blades, and by having 30 more than one or two blades, it will more securely hold the base against movement.

It is preferably desired to have one of the fastening means rigidly secured to the post and the other removably secured so that 35 when it is desired to arrange the posts upon the base, the removable fastening member may be quickly and readily removed so that the reduced portion 10 may be inserted between the rails 6, the rigid member having 40 its lower end engaging beneath the plate and the removable fastening member may then be replaced so that the post will be securely held against movement. From this it will

be seen that I have provided a simple and durable post supporting base, which is preferably arranged within the ground, the upper end thereof being disposed slightly above the surface of the ground so that the posts or poles may be readily engaged therewith. The poles or posts may be either constructed 45 of wood or metal, if desired, while the base portions are preferably formed of metal. It will be apparent that the device is extremely simple in construction and can be manufactured at comparatively low cost.

While I have shown and described the preferred form of my invention, it will be obvious that various changes in the details of construction and in the proportions may be resorted to for successfully carrying my 50 invention into practice without sacrificing any of the novel features or departing from the scope of the appended claim.

What I claim is:—

The combination with a base having a flat 65 top plate at one end, spaced parallel guide rails carried by one end of said base and having oppositely disposed inclined side walls, of a post adapted to be arranged between said guide rails, fastening members 70 having an engaging point at one end, said engaging point projecting at right angles to the body of the fasteners and adapted to penetrate the post, and a flat portion formed at the other end of each of said fastening 75 members, said flat portion projecting in the same general plane as the engaging point and adapted to be engaged beneath the flat top plate to retain the post in position upon the base.

In testimony whereof I hereunto affix my signature in the presence of two witnesses.

WILLIAM B. WADDELL.
